UNITED STATES PATENT OFFICE.

HENRY J. SOMMER, OF HOLLIDAYSBURG, PENNSYLVANIA.

SAFETY-TRAP FOR SEWERAGE SYSTEMS.

1,164,882.

Specification of Letters Patent. Patented Dec. 21, 1915.

Application filed March 31, 1914. Serial No. 828,564.

To all whom it may concern:

Be it known that I, HENRY J. SOMMER, citizen of the United States, residing at Hollidaysburg, in the county of Blair and State of Pennsylvania, have invented certain new and useful Improvements in Safety-Traps for Sewerage Systems, of which the following is a specification.

My invention relates to sanitary appliances and particularly to traps for sewerage systems.

The main object of my invention is to prevent floods in the sewerage systems of hospitals, factories, department stores and other public places caused by the clogging of the soil pipes.

In hospitals, and particularly in hospitals for the insane, the patients are liable to place all kinds of extraneous matter in the toilets, such as sheets, towels, pillow cases etc., and this often causes a damming back of the sewage and consequent flooding of basements and the necessity of tearing up the sewerage system and putting the institution to a very large expense. Almost all public institutions are liable to loss from this cause. In department stores and factories, the customers and employees throw pieces of cloth into the toilets thus causing sewerage floods, and the same is true of railway stations.

A further object of my invention therefore is to prevent such floods by the use of traps so designed that if there is any stoppage of sewage flow from any cause, an alarm will be sounded and notice given so that the sewerage system may be immediately cleared out.

A further object of the invention is the provision of means to prevent the passage to the sewer pipes of articles which would tend to clog these pipes.

A further object is the provision of traps so constructed as to permit the ready discharge into a main trap of articles such as towels, pieces of cloth, etc., which would ordinarily clog the sewer pipes.

Still another object is to provide alarm means sounded when the main trap is clogged, and individual alarms connected to the waste pipes leading from each toilet

which will sound an alarm when these soil pipes become clogged.

My invention is illustrated in the accompanying drawings wherein—

Figure 1 is a perspective view of a sanitary system constructed in accordance with my invention. Fig. 2 is an enlarged vertical section of a waste pipe leading from a toilet and the alarm connected thereto. Fig. 3 is a plan view of the construction illustrated in Fig. 1. Fig. 4 is a longitudinal section thereof on the line 4—4 of Fig. 3. Fig. 5 is a cross sectional view on the line 5—5 of Fig. 3. Fig. 6 is a cross sectional view of a toilet hopper showing diagrammatically the means for giving a signal in case the hopper becomes clogged.

Corresponding and like parts are referred to in the following description and indicated in all the views of the accompanying drawings by the same reference characters.

Referring to these drawings, 2 designates the main trap or receptacle into which all of the toilets discharge and from which a soil pipe 3 extends to the main sewer, the pipe 3 being shown as provided in its length with a trap 4 of any suitable construction and designed to prevent the return passage of gas from the sewer.

The receptacle 2 is shown as elongated and as having a rounded bottom and a flat top, though other forms of receptacle might be used. In its top it is provided with a plurality of handholes designated 5 adapted to be closed by gas-tight covers. The receptacle 2 is divided into a plurality of compartments, each compartment corresponding to one toilet by means of vertically disposed bars 6. In Fig. 1 two toilets are shown and therefore the receptacle 2 is divided into two compartments by two sets of bars 6. One set of these bars is shown as disposed at the middle of the receptacle 2 while the other set is disposed at the exit end of the receptacle so as to control the passage of material to the soil pipe 3. These bars are preferably arranged about two and one-half inches apart and are simply intended to prevent the passage of extraneous material such as rags or wads of paper to the pipe 3.

The toilets may be arranged in batteries

so that all shall empty into the one trap or receptacle 2. As shown there are two toilets. The toilets are designated 7 and may be made of any suitable construction. The contents of the toilets pass through the usual traps 8 and waste pipes 9. Each waste pipe terminates at its lower end in a trap 10 so constructed as to facilitate the passage of clothing, sheets, towels, etc., into the main trap or receptacle 2. As illustrated in Fig. 2, this trap 10 has one bend which discharges upward and which is flared at its discharge mouth as at 11, this discharge mouth being therefore relatively large so as to offer the least possible obstruction to the passage of material into the receptacle 2. The traps 8 may be dispensed with as the traps 10 though allowing the passage of cloth and extraneous matter will prevent the back passage of sewer gas. The traps 8 therefore are simply cumulative in their action as regards the passage of sewer gas.

Each compartment of the receptacle 2 is connected on one side near the top with a by-pass pipe 12 which is of sufficient size to accommodate the ordinary flow of sewage should extraneous material clog the bars 6 and thus dam up the sewage within the receptacle 2 and prevent its passage through the outlet end of the receptacle. This by-pass pipe 12 at one extremity is downwardly bent as at 13 and then connected by means of the trap 14 to the soil pipe 3.

Disposed adjacent the discharge end of the pipe 12 is an upwardly extending pipe or chamber 15, and extending through this chamber is a rod 16 of electrically conductive material, the lower end 17 of which projects into the pipe 12 and is so formed as to make electrical engagement with any water flowing through the pipe 12, the rod 16 being bent in the direction of flow of the water as illustrated. This rod 16 is connected in a normally interrupted circuit with a battery 18 and a bell 19 by the wires 20, one of the wires being grounded to the main discharge pipe in any suitable manner. It will be obvious now that upon the passage of water through the pipe 12, the water will form a conducting medium closing the circuit between the rod 16 and the metallic pipe and thus close the connection through the bell and cause the bell to sound or cause any other desired signal to be actuated.

In order to give an alarm in case any one of the waste pipes becomes clogged at the trap end, I support adjacent each waste pipe a vertically extending pipe 21 as illustrated in Fig. 2. This pipe 21 is preferably about eighteen inches long, of one inch galvanized pipe fitted to the waste pipe 9 at its lower end by a 45° L 22 and at its upper end connected to the waste pipe by a service T having a 45° arm, the angles of the T and of the L extending downward and toward the

waste pipe. If clogging takes place in the trap 10, or in trap 2 and by-pass 12, there will be a damming back of the sewage both in the pipe 9 and in the pipe 21 connected therewith.

Disposed within the upper end of the pipe 21 are the contacts 25 which are spaced from each other and connected in a normally open circuit with an electric bell and a battery 27. As soon as the sewage rises sufficiently within the pipe 21 to cause the water to submerge the lower ends of the contacts 25, the circuit will be completed, the water acting as a conducting medium between the spaced contacts 25, and the electric bell will be sounded or other signal given, thus notifying the engineer or plumber that the particular waste pipe has become clogged. He can immediately remove the obstruction from the trap and thus prevent flooding of the toilets and flooding of the basements of store rooms, etc.

While I have illustrated electric bells as being connected to the several traps and to the by-pass pipe, it will be of course understood that where many toilets are used in one building, an enunciator may be employed and the particular location of the trouble may be thus definitely pointed out.

In Fig. 6 I show a toilet hopper of an ordinary form, that is, of the cast porcelain type, this hopper being designated generally 7, and it may be of any suitable form or construction. Entering into the hopper preferably at the rear end thereof, is a small piece of pipe 29 which is downwardly extended as at 30. Disposed in this pipe are the electric wires 31 which at their ends are spaced from each other and disposed adjacent the mouth of the pipe 29. The other ends of the wires are connected in an electric circuit with a battery and a bell 32 or other suitable signal. It is obvious now that if the hopper becomes clogged or the trap of the hopper becomes clogged, it will cause a damming back of the sewage and this would eventually overflow from the hoppers. This will of course close a circuit through the wires 31 and the electric signal and an alarm will be sounded, this alarm indicating plainly the source of trouble.

It will be obvious that ordinarily and where all the pipes are free, the sewage will flow through the receptacle 2 and be discharged into the soil pipe 3 and thus into the sewer. If the bars 6 become clogged, the receptacle 2 may be readily cleaned out through the handholes 5. Inasmuch as each compartment of the receptacle 2 is individually connected to the by-pass pipe 12, it will be obvious that the clogging of an upper compartment will not affect the passage of material through the lower compartment. It will be also plain that when passage from the receptacle 2 is impeded sufficiently and the water rises in the receptacle 2, it will

commence to flow out through the by-pass pipe and an alarm will be immediately sounded. Thus while passage for the water is provided by means of the by-pass so that 5 damage will not occur from this damming back of sewage in receptacle 2, yet an alarm will be sounded which will indicate that there is trouble and permit the trouble to be removed. The same is, of course, true with 10 regard to the alarms showing a clogging of the pipes 9.

The trap 2 and the traps connected to the waste pipes may be constructed of iron, steel, concrete or any other substance that 15 will be water-tight and gas-proof, but preferably these several traps and receptacles will be made of cast iron.

It will be seen that I have provided electric signaling mechanism for the main receptacle or trap, for the waste pipe entering 20 the trap, for the hoppers or toilets connected to the waste pipes, and also provided signals for the by-pass so that whenever any one of these elements becomes clogged thus causing 25 the sewage to overflow, an alarm will be sounded. By providing a plurality of alarms connected to the several parts of the apparatus, it is obvious that I avoid the necessity of tearing out the plumbing of an establishment to find out where the clogging 30 occurs.

While I have illustrated what I believe to be the best form of my apparatus, I do not wish to be limited thereto as it is obvious 35 that the principle may be embodied in many different ways.

What I claim is:

1. In a sanitary system, a receptacle, a soil pipe leading from the receptacle, 40 partitional means dividing the receptacle into a plurality of intercommunicating compartments, waste pipes leading into the several compartments, hand holes opening into the compartments and indicating means associated with the several compartments and pipes to designate stoppage therein and the particular waste pipe that has been stopped.

2. In a sanitary system, a receptacle, a soil pipe leading from the receptacle, a by- 50 pass pipe connecting the upper portion of the receptacle to the soil pipe, indicating means associated with the by-pass, partitional means dividing the receptacle into a plurality of intercommunicating compartments, waste pipes leading into the several compartments, hand holes opening into the compartments and indicating means associated with the several compartments and

55 pipes to give warning of abnormal rise and stoppage of sewage in the receptacle and 60 designating the particular pipe in which stoppage has occurred.

3. In a sanitary system of the character described, a receptacle connected at one end to a sewer, a plurality of sets of barriers disposed within the receptacle preventing the passage of extraneous matter through the receptacle but permitting the passage of liquid material and dividing the receptacle into a plurality of compartments, waste pipes 65 connected one to each compartment and discharging thereinto, a by-pass pipe connected to the upper portion of each compartment and to the sewer, and an indicator associated with the by-pass pipe. 70

4. In a sanitary system of the character described, a receptacle, a pipe leading therefrom at one end to a sewer, a plurality of sets of bars dividing the receptacle into a plurality of compartments, a plurality of 80 waste pipes connected one to each compartment and discharging thereinto, a by-pass pipe connected to the upper end of each compartment and discharging into the sewer, indicating means coöperating with 85 the by-pass pipe and other indicating means associated and coöperating with the waste pipe. 75

5. In a sanitary system of the character described, an elongated receptacle connected 90 at one end to a sewer, a plurality of sets of vertically disposed bars dividing the receptacle into compartments but permitting the passage of water through the receptacle, a by-pass pipe having a connection to the upper 95 end of each compartment and discharging into the sewer, a vertical chamber disposed in the length of said by-pass pipe, indicating means coöperating with the chamber and by-pass pipe, a plurality of waste 100 pipes extending downward into the receptacle and each discharging into one of said compartments, a trap formed at the lower end of each waste pipe, said trap extending upward and having a relatively large and 105 outwardly flaring discharge mouth, a vertical pipe disposed parallel to each waste pipe and connected at its upper and lower ends thereto, and indicating means for each of said waste pipes. 110

In testimony whereof I affix my signature in presence of two witnesses.
